(57) **CLAIM**

The ornamental design for a shipping and display rack, as shown and described.

DESCRIPTION

FIG. 1 is a disassembled perspective view of the shipping and display rack according to the present invention.

FIG. 2 is an assembled perspective view of the shipping and display rack according to the present invention.

FIG. 3 is an assembled perspective view of the shipping and display rack according to the present invention showing products packaged therein.

FIG. 4 is an assembled top view of the shipping and display rack according to the present invention.

FIG. 5 is an assembled front view of the shipping and display rack according to the present invention. The assembled rear view is identical to the assembled front view.

FIG. 6 is an assembled left side view of the shipping and display rack according to the present invention. The assembled right side view is identical to the assembled left side view; and,

FIG. 7 is an assembled bottom view of the shipping and display rack according to the present invention.

The broken lines in all views are for illustrative purposes only and form no part of the claimed design.
